Samuel Parker

Sellers' Patent

Spun July 9, 1803. July 9, 1803

The Schedule referred to in these Sellers' Patent Making part of the same, containing a description, in the words of the said Samuel Parker himself, of his mode of carrying, and finishing leather of all kinds -

This consists in extending, smoothing, consolidating, splitting, leaching, cutting, cramping, oiling, stuffing, stamping, or printing, blacking, drying, slicking, tripling, polishing, glazing, or finishing - which is performed by a machine or machine, contained in a frame, the size of which may be according to the work. That is to say, if whole hides are intended to be done at one operation, in each part of the finishing, the frame of the machine must be as wide as the hide and the rollers or nuts and beam smaller, to admit the outer sides of the skins to be doubled while the single part only passes between the rollers and nuts and beam - repeating the same and performing a part at a time. The frame if larger or smaller will alter the proportion only not the construction or principle of the machine, which consist principally of a certain number of roller, to perform the different parts of the work; all at the same time, placed in different parts, and although an horizontal position hath been preserved, it is not a matter of consequence: as the rollers may be placed in any position or number, the constructor please, that will perform the works. The different sets of rollers, are for different work, and may generally be placed as the first. The number proportion and movement being nearly the same. Two large and one small, the small one in the center, placed horizontally, to be from one to two thirds less than the large; to have a cog wheel on the outside of one end of each roller of equal size or one on the centers roller; on the inside and next to the part, of the same size, or larger which will make the large rollers turn an equal or greater number of times with the small, which motion performs a slicking, slicking operation. The first set of rollers are intended

to extend smooth, consolidate, and thick the skins or hides, after being properly prepared, which operation fits or prepares them for splitting. The second set of rollers or nuts are intended for scarring and washing skins or hides. the nuts or rollers may be placed in a circular form the small 4 three or more placed round it, one under and two at the side of the under and center all having a proper bearing on the center one, forming halfcircle and one placed above the center, which are enclosed in a cistern. They may also be placed in a circle having one placed in the center then two or more courses round it: to have a proper bearing on each other and to one or more of the nuts or rollers may be attached sticks, or scrapers brush or brushes, or some of the rollers may be fluted, or any other article the operator may chuse to substitute by detaching the sticks scrapers brushes, and so forth from the above, the principle may be applied to the washing of linen, wooden, or any other fiable substance. The ends of the rollers may turn on turnables or small rollers or multiplying shells or being expert the ends of the rollers with steel or other metal or hard points may turn in sockets of any suitable metal all of which would overcome the friction of necessary. The third set of rollers or nuts are to receive the articles from the cistern and are to be furnished with sticks or scrapers, to strike the leather dry there will be also a board moving from side to side of the skin or hide, with a quick alternate motion to cleanse and loosen the same the skins or leather having passed through the last process is then cut into garters for men, women, or children, and are cut in one entire piece or two pieces except the soles, the same to be crimped on a foot toe, made for that particular purpose either of wood or iron or any substance suitable for the purpose with a joint in the foot or instep in such a manner, so that the toe instep or foot shall drop or turn downward until the leg is placed on the toe and tacked at the heel and the toe brought to its proper place again. or there may be a joint in the ankle the foot split in two parts and turn up each way, or it may be done by the leg and foot being in two parts, or it may be done by a moveable piece or pieces of wood, iron or any other substance suitable placed at the heel and running each or either way, stitched by screws, keys, axes or wedges after the leather is tacked thereto, being thus placed smooth on the foot toe remain in that

stitution until dry, then finished into moraces, or other way, and made on right and left last. Diverses legs or any other kind, may by this process be made into moraces or other leather finished and formed for the boot maker in a very superior stile one which will be a security against all manner of dirt originating in the present mode of stretching, cramping & finishing by curriers and boot makers in the inside of the boots and which generally soils the stockings. The ailing stuffing and blacking is performed by the under roller of each prepared by being covered with bimber or rollers knit and stuffed or any other thing proper to perform the operation. the oil stuffing and blacking are placed under each receiving roller in a trough or box long enough to receive the rollers to turn in the same. The leather is inserted through that and the next roller, at the conclusion of the blacking there should be a piece of rough leather, or cloth follows the skin, to prevent the ailing the upper roller. Unles the roller is made with a spring, or fall to drop the moment the skin leaves the rollers, the stuffing is prepared by one or more sets of nuts, and rollers placed two to a set, horizontally, one set above the other, to have a proper bearing with each other, side ways, and geared cornerways. the nuts and rollers all turn inward, from the top downward, receives the stuff at the top, and passeth through the whole number of sets more or less, the under set, to be the clipping rollers, the other, nutts, under which should be a trough to receive the stuff thus prepared: the same principal will answer a most valuable purpose, for reading and mixing of clay for making of bricks, Pottery or any other purpose or for working mortar of all kinds or for grinding of apples. - The blacking for what is called waxed leather may have the roller placed a little circular and have a roller on the side of it to size the leather, as it leaves the blacking roller, having the leather come through blacked and sized; or the blacking may be mixed with sizing, omitting the extra roller above, the operation being performed at once passing, the stripping is performed by the under roller being covered with strips of wooden, hatt, or cloth, or any other thing suitable for the work placed in strips as wide as the stripe is to be, and they as wide as the stripe. it may also be performed, by a board as large as the skin being covered with the stripes as before mentioned, and poised on the skin stamping and printing as performed by two or more rollers placed horizontally, one of which

rollers shall be made of iron, steel, brass, copper, or any hard material, on which shall be carved or engraved, such figure or figures as are intended to be imprested on the leather, or it may be performed by taking one roller with the desired figure or figures and ink the same by hand or any other force. The striking may be performed by rollers placed the same as the first, the size, proportion, and movement the same as the first, one of which shall be suitably covered, for cutting the leather out before and after blacking. The polishing, glazing and finishing may be performed by rollers the number proportion and movement the same, as the first mentioned, but much smaller, will stand in an horizontal direction, the small one in the middle the large one to be made of iron, steel, brass, composition, wood or any hard material to be turned with threads, the whole length of the roller, or any part or parts of it, it may also be performed by a table being placed on rollers horizontally, or angularly, the leather placed on the table and the table moving forward & backwards on the rollers, while the polisher, or stcker, move from side to side, crosting the table. The splitting is performed by two or more knives the length according to the number, the greater the number, the less the friction made in an oval or in the form of a half moon sett in a frame, carriage or block, in sockets of iron or some hard material if more than two place them as near each other as can be, and follow in direct course after each other, standing a little back from the leather placed in the center of the frame, carriage or block to move horizontally in grooves or through mortices, and cut each way, or in a back or angle direction, to cut but one way, or the knives may be sett to cut but one way, the frame, carriage or block moving horizontally, back, or angle ways the leather is moved or drawn by two nuts or rollers placed so near the knives as possible passing by a beam which governs the thickness, by being moved to any gage desired there confined by keys, screws, or wedges, the leather kept close to the beam by a spring which comes close up to the knives, they moving by the side of the beam splits and divides the leather as it passes, the grain side goes through the nuts or rollers, the other part falls down by the side and over the spring, the leather thus divided in many cases is worth nearly or quite as much the part split off as the grain side which has heretofore

been quite lost in unskillful shavings, it may also be performed by passing between two rollers, placed instead of the beam and going splitting the leather as it passes through the roller next to the nut to govern the thickness, by moving it nearer to or further from the skins, the leather extending underneath the roller by two other rollers, the splitting knives are set in operation by a shaft moved by a plow-horse or finisher which is set in operation by a shaft moved by a crank on which is a lantern or cog wheel which gives motion to a large wheel and sets the whole machine in operation in whole or part only, by shifting the bandage, or it may be done by cog-wheels instead of bandages, the power which sets the whole of the rollers and other works in motion may be either water, steam, wind horse or cattle by hand or any other force sufficient for the work. The utility and superiority of my method of currying and finishing leather of all kinds consists in the construction of the machine which may all be kept working at the same time doing every part of the business at once or any one part separately without the trouble of continually clearing the tables thus time is saved, labor is saved and the ingredients are saved and the leather made better in quality & the part split off from the skin equally as valuable as what was usually saved by the old method, another valuable consideration is that gators and boots can be made actually into morocco after the legs are cut, crimped, and strained and shaped ready for the workmen to sew at. June 27th 1803

Signed in presence of

William Thornton
Ezra Tilden

Samuel Parker

District of Columbia, City of Washington 28th June 1803 then personally appeared Samuel Parker Esquire, of Bellmea in the County of Middlesex, State of Massachusetts, above named, and made known unto that he verily believes that he is the true original inventor or discoverer of the art or improvement above specified and referred to, for which he solicits a patent before me —

William Thornton

not necessary
